INVENTOR.

Hazel H. Carter

BY

James V. Ramsey

ATTORNEY.

UNITED STATES PATENT OFFICE.

HAZEL H. CARTER, OF NORWOOD, OHIO.

CAN OPENER.

Application filed May 28, 1927. Serial No. 195,118.

My invention relates to can openers of the type requiring cutting action to sever the top from the body of the can.

The primary object of my invention is to 5 produce an efficient and effective can opener which can be readily and easily operated and one which is adapted to be readily adjusted for opening cans of varying sizes.

My invention consists in providing a bar 10 having a ratchet-toothed head and having a plurality of laterally projecting points with a pawl pivotally mounted on said bar and engaging said ratchet teeth under spring pressure, and a knife or cutter secured on the 15 end of an arm pivotally mounted to said bar and adapted to be oscillated forward and backward on its pivot by the hand of the operator.

My invention also consists in the construction, combination, location and arrangement of parts, as herein set forth and claimed.

In the drawings:

Fig. 1 is a plan view of the device in open or operative position ready to be applied to 25 a can;

Fig. 2 is a side or edge elevation;

Fig. 3 is a section on the line 3—3 of 30 Fig. 1;

Fig. 4 is a section on the line 4—4 of Fig. 1;

Fig. 5 is a section on the line 5—5 of 35 Fig. 1;

Fig. 6 is a sectional perspective of the pivot; and

Fig. 7 is a perspective view of the pivot 40 holder.

In the embodiment of my invention as illustrated and which shows a preferred construction, I provide a flat metal bar 1 having near one end eye 2 by which it may be hung or suspended on a hook or nail, and near said eye 2 I provide a bearing hole 3 to receive pivot 4 by which ratchet head 5 is pivotally secured thereto. Head 5 is provided with a plurality of laterally projecting metal points 6 adapted to be pressed into and pierce the can lid by pressure of the hand of the operator against the flat side of the bar.

50 Pawl 7, pivotally attached to bar 1, adjacent ratchet head 5, is held in engagement with the teeth 8 of ratchet head 5 by a spring 9, one end of which is attached to bar 1 and the other end of which bears in slot 10 in the 55 back of pawl 7.

The handle end of bar 1 is offset at 1' to dispose the portion 1'' in a different plane from the main portion of bar 1.

Bar 1 is provided near its center with a plurality of pivot bearings 11. Knife handle arm 12 comprises a flat metal bar of bent or angular shape with knife 13 secured upon its end and provided with bearing 14 by which said arm is pivotally attached to bar 1 by pivot pin 15 extending therethrough 60 and secured in detachable relation by catch or pivot holder 16, shown in Fig. 7. Said pivot pin 15 is provided with an annular groove 17 near one end and said catch or pivot holder 16 is formed of a flat spring 65 metal plate having one end bent upon itself at right angles to the other portion to form a handle 16'. Catch or pivot holder 16 is provided with notch 18 leading into an enlarged opening 19 whereby said catch 70 may be inserted into said annular groove 17 and sprung into position on said pivot-pin 15 to hold bar 1 and arm 12 in pivotal relation with each other.

Thus convenient and ready means are provided by which knife handle arm 12 may be pivoted to bar 1 in any of its bearings 11, depending upon the size of can it is desired to open.

Knife 13 is preferably formed in the shape 85 shown in Fig. 1 with a projecting point 13' at its forward end to readily enter the can when brought into cutting action and to assist in maintaining the cutting relation of the knife with the can during the oscillating 90 movement of the knife handle arm.

When the projecting points 6 of head 5 have been pressed into the lid of a can and the pawl is in the position shown in Fig. 1, the knife is brought into action against the 95 upper wall of the can by drawing the arm toward the bar with the hand, thereby producing a cutting action by the knife, and as the cutting proceeds the can is turned in an anti-clockwise direction, thereby permitting 100 pawl 7 to pass from one ratchet tooth to the next, depending upon the distance the can is turned. The pawl will hold the head from 105 turning and forms a resistance against the cutting movement of the knife on the handle. The movement of cutting comprises a scissors-like action by which the arm is oscillated back and forth toward and against the offset portion 1'' and thence apart therefrom during the operation.

The device is well adapted for removing the tops or lids of metal cans of cylindrical, square, oblong, or other shapes.

It will be understood that my invention 5 is capable of modification without departure from the scope or spirit thereof as defined in the claims.

What I claim as new and desire to secure by Letters Patent is:

- 10 1. A can opener comprising a bar, a ratchet head pivoted thereon and having holding points adapted to pierce the can lid and hold it from turning relative thereto, a spring actuated pawl mounted on said bar 15 and engaging the teeth of said ratchet head, a knife handle arm pivoted to said bar and having a knife on its end adjacent said ratchet head adapted to be drawn into cutting engagement with a cam by oscillating 20 movement of said arm upon its pivot against the resistance of said pawl and ratchet head.
2. A can opener comprising a bar having a ratchet head secured adjacent one end thereof and having its other end portion offset 25 set on a plane parallel to its main body portion, projecting points extending laterally from said ratchet head, a spring actuated ratchet engaging the teeth of said ratchet head, a knife handle arm pivoted to said bar and having a knife upon one end thereof whereby when said arm is actuated its handle 30 end will engage the offset portion of said bar when in closed position.
3. A can opener comprising a bar having 35 a ratchet head pivotally attached thereto, holding points on said ratchet head adapted to pierce a can lid to hold said head from turning, a pawl pivotally mounted on said bar and engaging the teeth of said ratchet 40 head to permit said bar to be rotated in a clockwise direction and to prevent backward movement thereof, a knife handle arm of bent formation pivoted to said bar and having a knife on one end thereof adapted to be 45 drawn into cutting engagement with a can by drawing the ends of said handle towards said bar and then drawing said bar upon its pivot to engage said pawl with a different tooth on said ratchet head, thereby auto-

matically sliding the knife handle arm and bar ready for the necessary cutting operation.

4. A can opener comprising a bar having a plurality of bearings between its ends, a ratchet head pivotally attached to said bar, holding points on said ratchet head, a spring actuated pawl adapted to engage the respective teeth of said ratchet head, a knife handle arm, and means for pivotally attaching said knife handle arm in any of said bearings 60 whereby cans of various sizes may be cut open.

5. A can opener as claimed in claim 3 wherein the means for detachably pivotally connecting the knife arm to the bar comprises a pivot pin having a head on one end and an annular groove near the other end, a catch comprising a spring metal plate having a notch in its end leading into a recess and having a handle adapted to force the converging ends of said catch into said grooves whereby said pin will enter said recess and hold said bar and arm in pivoted relation with each other.

6. A can opener as claimed in claim 1 75 wherein the knife handle arm is provided with a knife having a cutting edge terminating in a sharp angle point at its free end whereby said point will readily pierce the can and facilitate the cutting operation.

7. A can opener as claimed in claim 1 wherein the bar is offset at its handle end to bring the end portion in offset parallel relation with the main portion and whereby said offset portion will form a stop to arrest 85 the movement of the knife handle arm in its movement to cause cutting action of the knife.

8. A can opener as claimed in claim 1 90 wherein the bar is adapted to be moved on the pivot connecting the ratchet head and bar to advance the position of the knife for each successive cutting operation and whereby the pawl will be advanced into a different ratchet tooth to afford a bearing to resist the 95 forward cutting action of the knife upon the can.

HAZEL H. CARTER.
